UNITED STATES PATENT OFFICE.

WILLIAM FRANZ, OF BUCYRUS, AND WILLIAM POPE, OF CRESTLINE, OHIO.

IMPROVEMENT IN KNITTING-MACHINES.

Specification forming part of Letters Patent No. 105,187, dated July 12, 1870.

To all whom it may concern:

Be it known that we, WILLIAM FRANZ, of Bucyrus, and WILLIAM POPE, of Crestline, in the county of Crawford and State of Ohio, have invented a new and Improved Knitting-Machine; and we do hereby declare that the following is a full, clear, and exact description thereof, reference being had to the accompanying drawing and to the letters of reference marked thereon.

Figure 1 is a vertical section. Fig. 2 is a section on the line $\alpha\alpha$ of Fig. 1. Fig. 3 is a perspective view of a part of the cams.

Similar letters of reference denote like parts in each of the figures.

Our present invention relates to improvements upon the knitting-machine patented February 1, 1870, in Letters Patent of the United States No. 99,426; and consists in a novel construction of the cams which elevate the needles in working forward and backward.

In the annexed drawings, A is the cylinder of the machine, formed with a shoulder, H, on which the needles rest, being maintained upon the same horizontal plane until they reach the points at C and B. D and E are stationary guides, fastened to the cylinder and used in elevating the needles. K and L are stationary cams, formed as shown, on which the bent ends of the needles are carried when the needles are drawn down. J is an adjustable cam, secured to the cylinder by the set-screw F, which passes through lugs on the cylinder and also through a stud projecting from the cam J, and passing through a vertical slot in the cylinder. By turning the set-screw the cam J may be raised or lowered, as desired by the operator. At the angles formed by the cam-surfaces K and L and the horizontal shoulder H, latches B and C are pivoted. These latches are placed in slots cut in the cams L and K, or in equivalent notches formed to receive them. These latches oscillate upon their pivots, so as to stand either as shown in Fig. 1, at B, so that their upper surface forms an extension of the surface H, connecting it with the upper surface of the guides D or E, or to stand vertically, as shown at C, their points extending slightly above the surface of the shoulder H.

The operation of this machine is as follows:

When the bent heels of the needles, passing along the surface H, in knitting from left to right or forward, encounter the latch B, they will be thrown up over the guide D until, striking the cam J, they will be drawn down by the latter below its lower point, where, encountering the face of cam L, they will be forced up, passing between the guide E and the cam L and over the point of the latch C to the horizontal surface of the shoulder H.

If the machine is reversed, to knit from right to left, the heel of the advance needle, traversing the shoulder H, when it encounters the projecting point of the latch C, will cause it to swing on its pivot until its point is brought against the guide E, over which it and the rest of the needles will be carried to the cam J, which will force them down below its point, when they will be elevated by the cam K. The first needle, passing upward on the cam K, will cause the latch B to swing into the vertical position shown in the drawings for latch C, and thus, the latches operating automatically, the machine may be used to knit forward and backward.

We are aware of the patent granted to Dana Bickford on the 6th day of July, 1869, and claim nothing therein shown. We consider our machine an improvement on his. Our latches are differently constructed and arranged with reference to the other parts of the cylinder, and we dispense with springs used by Bickford.

Having thus described our invention, what we claim, and desire to secure by Letters Patent of the United States, is—

1. The combination, with the cylinder A, provided with the shoulder H, of the stationary guides D and E and pivoted latches B and C, substantially as described.
2. The combination of the cam J, stationary cams K and L, automatic latches B and C, and stationary guides D and E, substantially as shown and described.

In testimony whereof we hereunto subscribe our names in the presence of two subscribing witnesses this 5th day of May, 1870.

WILLIAM FRANZ.
WM. POPE.
